UNITED STATES PATENT OFFICE.

WILLIAM D. EYNON AND JAMES EYNON, OF PHILADELPHIA, PENNSYLVANIA.

APPARATUS FOR ROLLING RINGS, &c.

SPECIFICATION forming part of Letters Patent No. 554,482, dated February 11, 1896.

Application filed May 21, 1895. Serial No. 550,066. (No model.)

To all whom it may concern:

Be it known that we, WILLIAM D. EYNON and JAMES EYNON, citizens of the United States, residing in the city and county of Philadelphia, State of Pennsylvania, have invented a new and useful Improvement in Apparatus for Rolling Rings, &c., which improvement is fully set forth in the following specification and accompanying drawings.

10 Our invention consists of a novel construction of apparatus for rolling rings, &c., means being provided for causing the material which is rolled to assume a circular shape, and provision being also made for stripping the same from the rolls automatically without necessitating any additional attention on the part of the operator.

It further consists of novel details of construction, all as will be hereinafter set forth.

20 Figure 1 represents a side elevation, partly in section, of an apparatus for rolling rings, &c., embodying our invention, with the guide removed for clearness of illustration. Fig. 2 represents a plan view of the same. Fig.

25 3 represents a section on line $\alpha\alpha$, Fig. 1, viewed in the direction of the arrows. Fig. 4 represents a section on line $\gamma\gamma$, Fig. 1, viewed in the direction of the arrows. Fig. 5 represents a side elevation similar to Fig.

30 1, showing the relative position of the rolls and the guide for bending the metal into rings. Fig. 6 represents a section on line $x'x'$, Fig. 1, showing a piece of metal in the act of being bent.

35 Similar letters of reference indicate corresponding parts in the several figures.

Referring to the drawings, A designates the main shaft, which is supported in suitable bearings in the standards B, C, D, and E, 40 and has mounted thereon the pulley F, to which power may be applied.

G designates a roll mounted upon said shaft A intermediate the bearings C and D, said roll G having the arc J H K of reduced diameter, while the arc J L K is of greater diameter, 45 said latter arc being provided with a groove M.

N designates a gear which is mounted upon said shaft A, and is adapted to mesh with the pinion P, which is mounted upon the shaft 50 S, between the bearings Q and R, said pinion and shaft A having a feather and groove T

common thereto, whereby the shaft S rotates in unison with said pinion, but is capable of longitudinal movement relative thereto without causing any annular movement of the 55 pinion, any sidewise movement of the latter being prevented, since the same is held between the bearings Q and R, the holes through the same being of sufficient diameter to allow the rotation therein of said feather, as is evident.

U and V designate collars, which are attached to said shaft S, between the bearings Q and E, said collars being adapted to hold in position the lower bifurcated portion X of 65 the yoke W, the prongs of said portion X straddling the shaft S, as will be understood from Fig. 3, while the upper portion of said yoke may be provided with a suitable roller Y, which is adapted to engage the walls of a 70 cam-groove B' in the roll A', said yoke W being supported in position by means of the strap Z, which encircles said shaft A, as will be apparent.

The lower portion of the bearing D is provided with an extension C', which projects from a side thereof, within which rotates the bearing or cylinder E', the latter having attached thereto the grooved roller G', which is adapted to rotate at intervals in vertical 80 alignment with said roller G, the face D' of said bearing C' serving as a stripper to strip the material rolled from the small roll G', as will be hereinafter explained, the said G' having a journal H' which extends a short distance into the bearing in the lower portion of 85 the standard C.

A³ designates a guide employed to cause the metal blanks or rods employed to bend into the desired shape, the same consisting of the body 90 portion B³, which has an arm C³ by which it is attached to an adjacent standard, said body portion having the curved plain face D³, which is adjacent the small roll G', the edges of the curved face D³ terminating adjacent the two 95 large rolls, so that the metal rod or blank E³ will be compelled to assume the desired bend, as indicated in Fig. 6, the relative position of said rolls and guide being best seen in Figs. 5 and 6, said guide, however, being omitted 100 from the other figures for the sake of clearness of illustration.

The operation is as follows: Power having been applied to the pulley F, and the shaft A thus caused to rotate in the direction indicated, it will be seen that this rotation will be 5 imparted by means of the gear N to the pinion P, thereby causing the shaft S and the roll G' to rotate. In the meantime, however, the engagement of the roller Y of the yoke W with the cam-groove B' will cause the said shaft S 10 to move alternately from the left to the right, and vice versa, by reason of the contour of said cam-groove B', as seen especially in Fig. 2, it being remembered that said shaft S can move freely through the pinion P in either 15 direction, but is caused to rotate in unison therewith by means of the feather and groove T, thereby moving the groove in the roller G' in the present instance to the left of the groove M at certain intervals, as is evident.

20 If now a rod, bar or other piece of metal K' of the required length is interposed between the rolls L and G' at about the time that the point J is about to contact with said roll G', it will be seen that said metal K' will be caused 25 to assume the outline of a ring by reason of the contact of its extremity with the curved face D³ of the guide, as will be understood from Fig. 6, and as soon as the said roll G' has revolved, so that the reduced portion H is adjacent the roll G', the ring will be tightly in 30 engagement with said roll G', and at substantially this instant, by reason of the engagement of the yoke W with the cam in the manner described, the roll G' is caused to move 35 to the left, whereupon the edges D' of the bearing C' will act as a stripper and will push the completed ring off of said roll G', the latter being thus given a longitudinal or endwise movement without necessitating the stopping 40 of its rotation, as is evident.

In the preferred embodiment of our invention a roll A², having a raised groove portion B² and a recessed portion C², is placed under and in alignment with the roll G', the latter 45 and the said roll A² being substantially the same in all respects, and their positions relative to each other being indicated in Fig. 4, said roll A² being mounted on the shaft D², which rotates in suitable bearings E² and has 50 attached thereto the gear F², which meshes with the pinion P, so as to revolve in unison therewith, the function of said roll A² being to assist in supporting and shaping the material which is being rolled.

55 Having thus described our invention, what we claim as new, and desire to secure by Letters Patent, is—

1. In a device of the character described, a roll suitably mounted, and having one portion 60 of its periphery of reduced diameter, while the other portion thereof has a groove therein, a second grooved roll mounted adjacent the former roll, means for causing the material rolled to assume a curved contour, and means 65 for imparting a longitudinal movement to one of said rolls without stopping the rotation of either, substantially as described.

2. In a device of the character described, a pair of rolls, a portion of one of said rolls being of reduced diameter, the other portion of said roll having a groove therein, the second roll being adjacent said first-mentioned roll, means for rotating said rolls and means for imparting to said second roll a longitudinal movement, substantially as described. 70

3. In a device of the character described, the roll G constructed substantially as described, a shaft on which said roll is mounted, a cam secured to said shaft, a second shaft adjacent the former, a roll mounted on said shaft, a bearing for said roll having an edge thereof adapted to act as a stripper, means for rotating said shafts in unison, and means for imparting a longitudinal motion to one of said shafts, substantially as described. 80 85

4. In a device of the character described, the main shaft A having a roll G mounted thereon, a cam B', a gear N, a shaft S journaled in suitable bearings, collars U and V, a yoke W held between said collars, a pinion P mounted on said shaft S and adapted to mesh with said gear, a feather and groove common to said pinion and shaft S, a roll G' mounted on said latter shaft, and having an extension E', a bearing C' having an edge D' 90 adapted to act as a stripper, and a bearing J' for the journal H', the latter being attached to said roll G', substantially as described. 95

5. In a device of the character described, the roll G constructed substantially as described, a shaft on which said roll is mounted, a second shaft adjacent the former, a grooved roll mounted on the same, a bearing for said roll having an edge adapted to serve as a 100 stripper, means for rotating said shafts in unison, means for imparting a longitudinal motion to one of said shafts, a roll A² similar to said roll G located in alignment with the latter, a shaft therefor, and gearing for actuating 105 said shaft, substantially as described. 110

6. In a device of the character described, a pair of rolls arranged adjacent each other, a portion of one of said rolls being of reduced diameter, the other portion of said roll having 115 a groove therein, means for imparting to one of said rolls longitudinal movement without stopping its rotation, a third roll having a portion of reduced diameter, and mounted in alignment with one of said rolls, and means 120 for rotating said rolls in unison, substantially as described.

7. In a device of the character described, a series of rolls, means for rotating the same, means for causing the material rolled to assume a curved contour, means for imparting to one of said rolls a longitudinal movement with respect to the other, without causing a cessation of the rotation of either, and a stripper, the above parts being combined substantially as described. 125

8. In a device of the character described, a series of rolls, a portion of one of said rolls being of reduced diameter, means for caus-

ing the material rolled to assume a curved contour, means for rotating said rolls, and means for giving to one of the rolls a longitudinal movement with respect to the other without stopping the rotation of either, substantially as described.

9. In a device of the character described, a plurality of rolls suitably journaled, each having a portion of its periphery of reduced 10 diameter, and a groove in the other portion thereof, a grooved roll intermediate said

former rolls, means for causing the material rolled to assume a curved contour, means for rotating said rolls in unison, and means for imparting a longitudinal movement to the intermediate roll without stopping the rotation of either, substantially as described. 15
